SOUND TUBE HEAD SET

Thomas Albert Scanlon, Barrington, R.I., assignor to
Avid Corporation, Providence, R.I.

Filed June 8, 1970, Ser. No. 23,348

Term of patent 14 years

Int. Cl. D14—01; D24—02

U.S. Cl. D26—14

FIG. 1 is a perspective view of a sound tube head set, showing my new design;

FIG. 2 is a front elevational view thereof;

FIG. 3 is a rear elevational view of FIG. 1;

FIG. 4 is a right end view of FIG. 1;

FIG. 5 is a top plan view of FIG. 1;

FIG. 6 is a bottom plan view of FIG. 1.

The left end view and the right end view are identical. I claim:

The ornamental design for a sound tube head set, as shown and described.
